DESIGN FOR A HAIR WAVING MACHINE

Ernest Baum, Los Angeles, Calif.

Application June 4, 1934, Serial No. 52,049

Term of patent 7 years

To all whom it may concern:

Be it known that I, ERNEST BAUM, a citizen of the United States, residing at Los Angeles, in the county of Los Angeles and State of California, have invented a new, original, and ornamental Design for Hair Waving Machines, of which the following is a specification, reference being had to the accompanying drawing, forming a part thereof.

Fig. 1 is a side elevation of the hair waving machine, showing my new design.

Fig. 2 is a fragmentary rear view of the housing

for various meters taken on lines 2—2 in Fig. 1 and of the same machine.

Fig. 3 is a plan view of the upper extension of the same machine taken on lines 3—3 in Fig. 1.

Fig. 4 is a plan view of the lower extension or base of the same machine taken on lines 4—4 in Fig. 1.

I claim:

The ornamental design for a hair waving machine, substantially as shown and described.

ERNEST BAUM.
